ATTORNEYS.

UNITED STATES PATENT OFFICE

ALBERT HAPPEL, OF LOS ANGELES, CALIFORNIA

EXERCISING DEVICE

Application filed August 28, 1928. Serial No. 302,588.

My invention relates generally to that class of exercising devices embodying weighted bodies adapted to be manually lifted and manipulated to provide healthful exercise for the user. It is a purpose of my invention to provide an exercising device of this character, the weight of which is capable of being carried with the utmost ease and dispatch, so that more or less strength will be required on the part of the user to lift and manipulate the device, thus rendering the device adaptable for light and heavy exercises and by persons having more or less physical strength, to the end that the necessity and expense of providing a number of devices of respectively different weights will be dispensed with.

It is a further purpose of my invention to provide an exercising device of the above described character which is capable of being worn on the foot of a person as a shoe, and to which one or more weights are adapted to be applied and firmly secured against displacement, or removed at will with the utmost ease and dispatch so that the total weight of the device can be varied as desired for the purpose above set forth.

I will describe only one form of exercising device embodying my invention and will then point out the novel features thereof in claims.

In the accompanying drawing—

Fig. 1 is a view showing in plan one form of exercising device embodying my invention;

Fig. 2 is a vertical longitudinal sectional view taken on the line 2—2 of Fig. 1;

Fig. 3 is a transverse sectional view taken on the line 3—3 of Fig. 2 and looking in the direction of the arrows;

Fig. 4 is a transverse sectional view taken on the line 4—4 of Fig. 2 and looking in the direction of the arrows;

Fig. 5 is a bottom plan view of the sole portion of the device; and

Fig. 6 is a perspective view of one of a plurality of weights capable of being applied to the device.

Referring specifically to the drawing in which similar reference characters designate similar parts in each of the several views, my invention in its present embodiment comprises a body constructed to provide a sole

portion S and a heel portion H, both preferably in the form of metal plates of the contour shown in Fig. 1. The sole and heel portions are extensibly connected to permit the overall length of the device to be varied to accommodate feet of different sizes.

In the present instance this extensible connection between the sole and heel portions comprises a bar 10 of flexible spring metal seating at one end in a recess 11 formed in the bottom of the heel portion H and rigidly secured to the latter by rivets 12 so as to extend forwardly and to be slidably received in a longitudinally extending slot 13 formed in the sole portion S. The slot 13 communicates with the top surface of the sole portion S and is spanned intermediate its ends by a cross-bar 14 constituting a fixed stop against which a stop lip 15 formed on the free extremity of the bar 10 is adapted to abut to limit the fully extended position of the sole portion.

The sole portion is capable of being latched in any one of a plurality of selected extended positions, and to this end the bar 10 is provided with a longitudinal series of openings 16 into any one of which a pin 17 fixed to the sole portion and projecting upwardly into the slot 13, is adapted to be received to normally latch the bar against movement. However, the sole portion can be readily unlatched to permit its adjustment by the simple expedient of flexing the bar 10 to the position shown in broken lines in Fig. 2, in which the portion of the bar between the cross-bar 14 and the rear end of the sole portion S will be flexed upwardly as shown in broken lines in Fig. 2 to clear the pin 17 from the opening 16 of the bar in which the pin was previously received, so that by maintaining the bar in such flexed condition, the sole portion can be adjusted on the bar until another of its openings 16 registers with the pin 17, in which position the bar is released, and in returning to its normal position will again latch the sole portion against movement on the bar.

The heel portion H is provided with a U-shaped flange 18 of leather or other suitable material in which the heel of the foot is adapted to be received, while secured to the

sides of the flange 18 are the two sections of a strap 19 adapted to co-operate in embracing the foot, the strap being provided with a conventional buckle 20 for securing the strap in embracing relation to the shin portion of the foot. The sole portion S is also adapted to be secured to the foot, and to this end the sole portion is provided adjacent its side edges and substantially midway between its forward and rear ends with slots 21 through which a single strap 22 is adapted to be threaded as shown in Fig. 3, to extend across the bottom of the sole portion with its ends cooperating to embrace the forward portion of the foot, one end of the strap being provided with a conventional buckle 23 adapted to co-act with openings 24 in the other end of the strap in securing the latter in embracing relation to the foot, so that the two straps 19 and 22 will co-operate to firmly secure the device to the foot for wearing on the latter as a shoe.

The total weight of the device as above described is adapted to be readily varied by the addition of one or more weights designated generally at W, and for the purpose of illustration two of these weights are shown applied to the device. The weights are of identical construction and each is in the form 30 of a metal plate 25 of the same contour as that of the sole portion S.

The strap 22 is adapted to be utilized to detachably secure one or more of the weights W to the sole portion S, and to this end each weight is provided with a pair of slots 26 similarly positioned to the slots 21 of the sole portion so as to register with the latter slots when one or more of the weights underlie the sole portion as shown in Figs. 2 and 40 3. When a weight is to be applied to the sole portion the strap 22 is withdrawn from the slots 21 of the sole portion and then threaded through the slots 21 of the sole portion and the slots 26 of the weight so that the strap will extend across the bottom of the weight and is adapted to embrace the foot to secure the weight to the sole portion and the latter to the foot.

In order to prevent lateral shifting or displacement of the weight relative to the sole portion, a tongue and groove connection is provided which in the present instance comprises a rib 27 projecting from the bottom of the sole portion, the rib being of a contour similar to the contour of the sole portion and spaced from the marginal edge of the latter as shown in Fig. 5. The top surface of each weight is provided with a groove 28 adapted to receive the rib 27 and thus co-operates with the latter in preventing lateral displacement of the weight. The side walls of the rib and groove are oppositely inclined as shown in Figs. 3 and 4 so as to facilitate application of the weight to the sole portion.

It will be noted that the rib 27 is discon-

tinued at oppositely disposed points as indicated at 29 so that in the event the device is to be used for exercising without the addition of any of the weights W, the strap 22 can fit snugly against the bottom surface 70 of the sole portion. As the strap is of less thickness than the height of the rib the strap will be elevated out of contact with the floor when the rib is resting on the latter, thus preventing unnecessary wearing of the strap. 75

Each weight W is also provided on its under surface with a rib 30 which is adapted to be received in the groove 28 in the top surface of another of the weights so that in the event a number of the weights are to be used 80 they will be locked against relative shifting or displacement. The rib 30 of each weight is discontinued at oppositely disposed points as indicated at 31 to permit passage of the strap 22 so that the latter can snugly fit the 85 bottom surface of the weight for the same purpose as that described in connection with the rib 27 of the sole portion S.

It will thus be clear that one or more of the weights W can be readily secured to or removed from the sole portion to vary the total weight of the device, and that the strap 22 is utilized not only as a means for securing the sole portion S to the user's foot but also as a means of securing one or more weights 95 to the sole portion, and all in such manner that the weights will be fixedly held against shifting or displacement relative to each other and to the sole portion.

It will be understood that although I have 100 described the variation in weight of the device as being effected by the provision of one or more weights to the sole portion S, such variation could also be obtained by utilizing the heel portion H and providing suitable 105 weights for the latter.

Although I have herein shown and described only one form of exercising device embodying my invention, it is to be understood that various changes and modifications 110 may be made therein without departing from the spirit of the invention and the spirit and scope of the appended claims.

I claim:

1. An exercising device comprising a body 115 having a sole portion and a heel portion, means by which the body is adapted to be secured to the foot of a person for wearing on the foot as a shoe, weighted means underlying the bottom of the sole portion, and means for detachably securing the weighted means to the sole portion so that the weighted means forms the tread surface of the sole portion.

2. An exercising device comprising a body 125 having a sole portion and a heel portion, means by which the body is adapted to be secured to the foot of a person for wearing on the foot as a shoe, weighted means underlying the bottom of the sole portion and de- 130

tachably secured thereto to permit the total weight of the body to be varied, and coacting means on the confronting surfaces of the sole portion and weighted means for preventing lateral displacement of the weighted means on the sole portion.

- 5 3. An exercising device comprising a body having a sole portion and a heel portion, means by which the body is adapted to be secured to the foot of a person for wearing on the foot as a shoe, weighted means underlying the bottom of the sole portion and detachably secured thereto to permit the total weight of the body to be varied, and means for preventing lateral displacement of the weighted means on the sole portion comprising a tongue on the sole portion and a groove in the weighted means receiving the tongue.

- 10 4. An exercising device comprising a body having a sole portion and a heel portion and adapted to be worn as a shoe on the foot of a person, a weight adapted to underlie the bottom of the sole portion, and a single means for detachably securing the weight to the sole portion and the latter to the foot of the person.

- 15 5. An exercising device comprising a body having a sole portion and a heel portion and adapted to be worn as a shoe on the foot of a person, a weight adapted to underlie the bottom of the sole portion, and means for detachably securing the weight to the sole portion and the latter to the foot of the person comprising openings in the sole portion and weight adapted to register, and a strap capable of being threaded through the openings and of embracing the forward portion of the foot.

- 20 6. An exercising device comprising a body having a sole portion and a heel portion and adapted to be worn on the foot as a shoe, a weight comprising a plate adapted to underlie the sole portion and having substantially the contour of the latter, the sole portion and plate having openings therethrough adapted to register, and a strap capable of being threaded through the openings and to embrace the foot to secure the plate to the sole portion and the latter to the foot.

- 25 7. An exercising device comprising a body having a sole portion and a heel portion and adapted to be worn on the foot as a shoe, a weight comprising a plate adapted to underlie the sole portion and having substantially the contour of the latter, the sole portion and plate having openings therethrough adapted to register, a strap capable of being threaded through the openings and to embrace the foot to secure the plate to the sole portion and the latter to the foot, a rib projecting from the bottom surface of the sole portion, and a groove in the plate receiving the rib to prevent lateral displacement of the plate on the sole portion.

- 30 8. An exercising device comprising a body having a sole portion and a heel portion and

adapted to be worn on the foot as a shoe, a weight comprising a plate adapted to underlie the sole portion and having substantially the contour of the latter, the sole portion and plate having openings therethrough adapted to register, a strap capable of being threaded through the openings and to embrace the foot to secure the plate to the sole portion and the latter to the foot, a rib projecting from the bottom surface of the sole portion, a groove in the plate receiving the rib to prevent lateral displacement of the plate on the sole portion, and a rib on the bottom surface of the plate adapted to receive a groove in a second and identical plate also constituting a weight, through which the strap is adapted to be threaded to secure the second plate as well as the first plate to the sole portion to further increase the total weight of the body.

35 9. An exercising device comprising a body having a sole portion and a heel portion and adapted to be worn on the foot as a shoe, a weight comprising a plate adapted to underlie the sole portion and having substantially the contour of the latter, the sole portion and plate having openings therethrough adapted to register, a strap capable of being threaded through the openings and to embrace the foot to secure the plate to the sole portion and the latter to the foot, a rib projecting from the bottom surface of the sole portion, a groove in the plate receiving the rib to prevent lateral displacement of the plate on the sole portion, and a rib on the bottom of the plate discontinued sufficiently to permit passage of the strap across the bottom of the plate in engagement with the bottom surface of the plate so that the strap will be elevated out of contact with the floor when the rib is resting on the latter.

40 10. An exercising device comprising a body having a sole portion and a heel portion and adapted to be worn on the foot as a shoe, the sole portion being in the form of a plate having openings adjacent its side edges, through which a strap is adapted to be threaded to underlie the plate and embrace the foot to secure the sole portion to the foot, and means on the plate by which the strap is adapted to be elevated out of contact with the floor when the plate is resting on the latter so as to prevent wearing of the strap.

45 11. An exercising device comprising a body having a sole portion and a heel portion and adapted to be worn on the foot as a shoe, the sole portion being in the form of a plate having openings adjacent its side edges, through which a strap is adapted to be threaded to underlie the plate and embrace the foot to secure the sole portion to the foot, and means on the plate by which the strap is adapted to be elevated out of contact with the floor when the plate is resting on the latter so as to prevent wearing of the

strap comprising a rib projecting from the bottom surface of the plate.

12. An exercising device comprising a weighted body adapted to be worn on the foot as a shoe and having a sole portion and a heel portion, and means for extensibly connecting the sole and heel portions comprising a slot in one of the portions, a flexible bar on the other portion slideable in the slot, and means by which the bar can be latched in any one of a plurality of longitudinally adjusted positions in the slot, comprising a pin fixed in the slotted portion and projecting into the slot, and a plurality of openings in the bar, into any one of which the pin is adapted to be normally received, the bar capable of being flexed sufficiently to clear the pin so that the latter will be removed from the bar opening to permit adjustment of the bar.

20 13. An exercising device comprising a weighted body adapted to be worn on the foot as a shoe and having a sole portion and a heel portion, and means for extensibly connecting the sole and heel portions comprising a slot in one of the portions, a flexible bar on the other portion slideable in the slot, and means by which the bar can be latched in any one of a plurality of longitudinally adjusted positions in the slot and operable to release the bar when flexed so that the bar will be free for adjustment.

25 14. An exercising device comprising a body having a sole portion and a heel portion and adapted to be worn on the foot as a shoe, the sole portion having a slot therein, a flexible bar fixed to the heel portion and slideable in said slot to extensibly connect the sole and heel portions, the bar having a plurality of openings, a pin fixed in the sole portion and projecting to the slot of the latter to be normally received in any one of said openings to latch the bar against movement in the slot, the bar capable of being flexed sufficiently to clear the pin so as to permit adjustment of the bar, and a stop lip on the bar for limiting the adjustment of the bar in the slot.

30 15. An exercising device as embodied in claim 14 including a weight adapted to underlie the sole portion, the sole portion and weight having openings adapted to register, and a strap capable of being threaded through the openings and to embrace the foot to secure the weight to the sole portion and the latter to the foot.

35 Signed at Los Angeles, in the county of Los Angeles, and State of California, this 17th day of August, A. D. 1928.

ALBERT HAPPEL
